Patented Aug. 4, 1970

218,228

ALL-WEATHER BARN

Caleb G. Clarke, 1540 W. Market St.,
Akron, Ohio 44313

Filed Apr. 10, 1969, Ser. No. 16,665

Term of patent 14 years

Int. Cl. D25—04

U.S. Cl. D13—1

FIG. 1

FIG. 3

FIG. 4

FIG. 5

FIG. 6

FIG. 1 is a perspective view, looking down upon the all-weather barn, a horse and an attendant, as well as a tree being shown in phantom for illustrative purposes only;

FIG. 2 is end elevation thereof;

FIG. 3 is side elevation from the Y-arch open on right side;

FIG. 4 is a rear elevation;

FIG. 5 is side elevation from the Y-arch closed side of the building; and

FIG. 6 is a top plan.

I claim:

The ornamental design for an all-weather barn, as shown and described.
